BIMETALLIC SWITCH

Octavio Jose Alvarez, New York, N. Y., assignor,
by means assignments, of one-fourth to Maria
de Reitzes-Marienwert, New York, N. Y.

Application May 28, 1949, Serial No. 95,999

12 Claims. (Cl. 290—138)

1

My invention relates to a bimetallic switch, and more particularly to a bimetallic switch for use with water boilers, such as those provided in a coffee percolator, hot plates or the like.

It is an object of my invention to provide a bimetallic switch in which the contacts are opened suddenly and with great speed.

It is a further object of my invention to provide a bimetallic switch which has no friction contacts and no frictional or pivoting movements in the mechanical parts of the switch.

It is another object of my invention to provide a bimetallic switch with mechanical compression of the contacts while the switch is closed.

It is another object of my invention to adjust the temperature at which the switch works, from the outside of the switch without touching a current-carrying member.

It is another object of my invention to provide a bimetallic switch which is simple in construction and cheap to manufacture.

I achieve these and similar objects by providing a bimetallic strip, a spring arranged for snapping transition from one end position into another end position, a connection between the bimetallic strip and the snapping spring causing the spring to snap into the other end position when the bimetallic strip is hot, and a contact arranged for actuation by the spring.

In a first embodiment of my invention a member is provided which connects the snapping spring and the contact, the member being arranged for coming into engagement with the contact in the last part of the motion of the spring into the other end position under action of the bimetallic strip.

In one embodiment of my invention a U-shaped strip having a stationary end is provided, and a contact is rigidly connected to the other end of the U-shaped strip; a member shaped as a double stirrup connects the middle portion of the snapping spring to the leg of the U-shaped strip carrying the contact, and a threaded bolt is screwed into a threaded hole in the part of the double stirrup engaging the snapping spring and extends loosely through holes provided in the U-shaped strip and is arranged with its end near the middle portion of the bimetallic strip.

In another embodiment of my invention the bolt makes contact in the closed position of the switch directly with a counter-member and is pressed into contact-making position by an insulating member. If desired, an insulating plate may be arranged for being pushed between the bolt and the counter-member when the switch

2

opens, and resilient means actuated by the member pressing the bolt into contact-making position is provided for pushing and withdrawing the plate into and from operating position.

5 The novel features which I consider as characteristic for my invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a sectional elevation of one embodiment of my invention with the switch contacts closed at about two to three times the natural scale;

Fig. 2 is the same embodiment with the contacts open;

15 Fig. 3 is a sectional elevation of the same embodiment with open contacts and the restarting button pressed in;

Fig. 4 is a cross-section along the line 4—4 of Fig. 1;

25 Fig. 4a is a perspective view of a part of the device shown in Figs. 1—4;

Fig. 4b is a perspective view of the housing of the device shown in Figs. 1—4;

Fig. 4c is a perspective view of the contacts of the device shown in Figs. 1—4;

30 Figs. 5 and 6 are sectional elevations of another embodiment of my invention with open and closed contact, respectively, also at about two to three times the natural scale;

Fig. 7 is a cross-section along the line 7—7 of Fig. 6;

35 Figs. 8 and 10 are sectional side elevations of a third embodiment of my invention with the contact closed and open, respectively, and again at about two to three times the natural scale; and

40 Figs. 9 and 11 are cross-sections of Figs. 8 and 10 taken along the lines 9—9 and 11—11, respectively.

45 Referring now to the drawings, and first to Figs. 1 and 4, 10 is part of the bottom of an electrically heated vessel, such as the bowl of a coffee percolator, which is heated by an electric current which is controlled by the switch hereinafter described. For a reason to be more fully explained later, the part 10 of the bottom of the vessel is arranged a little higher than the remaining parts of the bottom such as the parts 12 and 14 (Fig. 4) so that the upper part of the switch to be described is situated in a recess of the bottom. The 50 parts of the switch are arranged in a housing

generally denoted by 16 and shown separately in Fig. 4b. The housing, preferably made of aluminum, comprises two end walls 18 and 20, a bottom 22 with a rectangular aperture 24, and a roof which consists of the marginal portions 26 and 28 which are provided with prong-like extensions 30 and 32. The end walls 18 and 20 are provided at their bottom ends with small apertures 34 and 36, respectively, for the insertion of the endwise extensions 38, 40 of a snapping spring 42 to be more fully described later.

The prong-like extensions 30 and 32 of the roof of the housing 16 are in contact with or even spot-welded to the bottom parts 12 and 14 of the vessel as will be clear from Fig. 4. A bimetallic strip 44 rests with its end portions on the marginal portions 26 and 28 of the roof of the housing 16 and is, while it is cold, in contact with the bottom part 10 of the vessel (Figs. 1 and 4).

A block 46 of insulating material is carried by the end wall 18 of the housing 16. A substantially U-shaped spring 48 is secured with its end portion 50 to the block 46. The end portion 50 is preferably slightly off-set with respect to the main body of the spring as will be seen from Fig. 1. The other end portion 52 of the U-shaped spring 48 is shorter than the end 50 and its outer rim 54 is bent at right angles to the end portion 52 so as to provide a seat for a block 56 of insulating material. The block 56 with a counter-block 58, also of insulating material, are secured to the end portion 52 of the spring 48 by means of a rivet 60. Between the blocks 56 and 58 is sandwiched the end of the stem of a T-shaped member 62, preferably of metal and shown separately in Fig. 4c, the outer rim 64 of which is bent at right angles with respect to the main portion of the member 62 so as to provide a proper abutment on the counterblock 58. The member 62 is provided with a hole for the rivet 60. The cross-piece 66 of the T-shaped member 62 carries two contacts 68 and 70 which are in electrically conductive connection with each other, preferably through the material of the cross-piece. The contacts 68 and 70 are in contact, when the switch is closed as in Fig. 1, with contact pieces 72 and 74, respectively, which are secured to the block 46 and to which the circuit controlled by the switch 9 (not shown) is connected. It will be understood that in the position of the switch shown in Fig. 1 the T-shaped member 62 with the contacts 68 and 70 short-circuits the contact pieces 72 and 74, whereas in the position shown in Figs. 2 and 3 it interrupts the electrical connection between them.

In the bottom part of the housing 16 a snapping spring 42 is penetrating with its end portions 38 and 40 into the apertures 34 and 36, respectively. The snapping spring 42, which is separately shown in Fig. 4a, is naturally slightly convex towards the interior of the housing 16 as will be seen from Fig. 1 which, however, shows the convexity of the snapping spring at an exaggerated scale for the sake of clearness.

In the center of the snapping spring 42 is provided a hole 76 through which the threaded end 78 of a bolt 80 passes loosely, i. e. at a certain distance of the perimeter of the hole 76. The bolt 80 is screwed with the threaded end 78 thereof into the lowermost part 82 of a connecting member generally indicated by 84 the shape of which is a double stirrup more clearly shown in Fig. 4. It consists of a strip the ends of which are bent into U-shape of different widths. The lowermost U-shaped part comprises the portions

5 82 and 86 which enclose between them practically without play the snapping spring 42. The lowermost U-shaped part is connected to the uppermost U-shaped part by an intermediate part 88 the length of which substantially corresponds to the distance between the snapping spring 42 and the lower portion of the spring 48 in the switched-in position shown in Figs. 1 and 4. The upper U-shaped part of the connecting member 84 comprises the portions 90 and 92 which enclose between them the lowermost bend of the U-shaped spring 48 and are separated from each other by a certain distance so that in the switched-in position of the switch the lowermost bend of the U-shaped spring 48 is in contact with the portion 90, as shown in Figs. 1 and 4, whereas in the open position of the switch it is in contact with the portion 92 as will be described in more detail hereinafter in connection with Fig. 2. The portions 86, 90 and 92 of the connecting member and the upper and lower portion of the U-shaped spring are provided with holes through which the bolt 80 or its end portion 78 pass with a clearance. The bolt 80 extends upwards so that its rounded end 94 is in the switched-in position shown in Figs. 1 and 4 a short distance below the bimetallic strip 44.

The operation of the device so far described is as follows: With the position of the switch shown in Figs. 1 and 4 the T-shaped member 62 with the contacts 68 and 70 is in contact with the contact pieces 72 and 74 and short-circuits the same. When the current is switched in by any means (not shown) the vessel or hot plate becomes hot and heats through the part 10 the bimetallic strip. The part 10 is preferably somewhat elevated with respect to the remaining parts of the bottom of the vessel so that some liquid will be left within the vessel while the part 10 becomes dry and actuates the bimetallic strip. The bimetallic strip bends in consequence of the heating and eventually reaches the position shown in Figs. 2 and 3. During this process it displaces the bolt 80 and therefore the snapping spring 42 a little whereas the U-shaped spring 48 is not yet affected. After the snapping spring 42 has passed its mean position in which it is flat it turns with a snap into the position shown in Fig. 2 in which it is concave with respect to the interior of the housing 16. In the latter part of this motion of the snapping spring 42 the uppermost bend 92 of the connecting member 84 which had followed the motion of the snapping spring 42 owing to its connection with it by its lower U-shaped part comes into contact with the lower bend 52 of the U-shaped spring 48 and suddenly opens the contacts 68-74 (Fig. 2). It will be understood from the foregoing that the temperature at which the switch opens the contacts can be controlled by changing the setting of the bolt 80 within the lowermost bend 82 of the connecting member 84 by turning the head 96 of the bolt 80.

The parts shown in Figs. 1-4 at the bottom serve for re-setting the switch after it has broken the circuit. A support 98 which is stationary with respect to the housing 16 is provided with a flanged central hole 100 in which a press button 102 is slidably movable. The press button 102 is in contact with a spring member generally denoted by 104 and comprising a metal strip provided with a central hole 106 which is in alignment with a corresponding hole 108 in the press button 102 in order to have access to the head

96 of the bolt 80. At both ends the strip 104 is bent as at 110 and is secured in apertures 112 of the support 88. About half-way between the bent portions 104 and the hole 106 of the strip 104 the latter is provided on either side with a U-shaped bend 114 turning towards the snapping spring 42.

The operation of this device is as follows:

When the switch is open and the bimetallic strip 44 has returned to its initial position shown in Fig. 1 the press button is pressed upwards and the U-shaped bends 114 press the snapping spring into its initial position shown in Fig. 1 whereby the connecting piece 84 is brought back to its initial position and the contacts 68—74 are closed. Then the pressure on the button 102 is relieved so that it returns to the position shown in Fig. 1, the switch being ready for use.

If the press button 102 is actuated while the parts of the switch are still in the position shown in Fig. 2, i. e. the bimetallic strip 44 is bent downwards, the snapping spring 42 cannot move upwards with its middle portion because the bolt 80 hits the bimetallic strip 44 and therefore the connecting member 84 cannot move the whole distance upwards. The parts assume then the position shown in Fig. 3 where the snapping spring 42 has a multiple bend and the contacts 68—74 are still open.

Referring now to the embodiment shown in Figs. 5-7, the switch is located inside a structure 120 of insulating, preferably ceramic material. On top of the structure 120 is arranged the heated part 122 such as the bottom of a water boiler and underneath the structure 120 is an insulating plate 124 provided with an aperture 123 for a press button 128 which preferably consists of insulating material. The press button 128 is provided with a central aperture 130 in order to render the head 132 of a screw bolt 134 accessible by means of a screw driver (not shown). Parts 120, 122 and 124 are held together by any suitable means (not shown).

Below the heated part 122 is arranged a double bimetallic strip 136 and below this strip an asbestos strip 138 which rests with its ends on two shoulders 144 and 146 of the structure 120 (Fig. 7). The asbestos strip 138 is with its center in contact with the end of a metal leaf spring 140 which is carrying a contact piece 142. The other end of the leaf spring 140 is connected to one end of a heating winding 148 and both are clamped together by a bolt 150 with nut 152 securing the leaf spring 140 to the structure 120.

A snapping spring 154 is provided with its mid-portion 156 opposite to the asbestos strip 138 and the leaf spring 140 with contact piece 142. One end of the snapping spring 154 is bent in U-shape as at 158 and 160 and rests against the structure 120 and the insulating plate 124 (Fig. 7). The other end 162, 164 of the snapping spring 154 is bent approximately in Z-shape and secured to the structure 120 by means of a screw bolt 166 with nut 168. A current lead 170 is connected to the snapping spring 154 by means of the bolt 166. The mid-portion 156 of the snapping spring 154 is provided with a threaded hole 172 into which the screw bolt 134 is screwed. It will be seen from Fig. 7 that in the closing position of the switch an electrical connection is established between the current lead 170 and the end of the heating winding 148 through the snapping spring 154, the screw bolt 134, the contact piece 142, and

the leaf spring 140. In this position of the switch the snapping spring 154 is slightly convex towards the contact piece 142 whereas in the opening position of the switch shown in Fig. 5 it is concave with respect to the contact piece 142.

A slidable plate 172 of insulating material is arranged at right angles to the snapping spring 154 and the leaf spring 140 (Figs. 5 and 6) which in the opening position of the switch shown in Fig. 5 enters between the screw bolt 134 and the contact piece 142 thus interrupting any arc which might occur during the switching operation. The structure 120 is provided with a strip 174 of insulating material at the spot turning towards the forward edge of the plate 172, so as to provide a complete separation of the screw bolt 134 and the contact piece 142 in the open position of the switch.

In order to close the switch the press button 128 is moved upwards until it reaches the position shown in dotted lines in Fig. 6. The button is provided with a bevelled upper surface 176 which during this motion comes into engagement with a spring 178 the shape of which will be seen from Figs. 5 and 6. The spring 178 is secured to the structure 120 by means of a bolt 180 with nut 182 and one of its ends is shaped as guide 184 for the plate 172. The other end 186 of the spring 178 engages a hole 188 in the plate 172. The natural position of the spring 178 is shown in Fig. 5 where it holds the plate 172 in the arc-interrupting position. When the switch is closed by means of a pressure on the button 128 the spring 178 is brought by the bevelled end 176 of the button into the position shown in Fig. 6 where it retracts the plate 172 and holds it in retracted position so that the screw bolt 134 can make contact with the contact piece 142. When the button 128 is relieved from pressure and returns into the position shown in full lines in Fig. 6, the plate 172 abuts against the screw bolt 134 and the spring 178 remains in the position shown in Fig. 6.

The operation of this device is as follows:

With the switch being open and the parts being in the position shown in Fig. 5, in order to close the switch, the press button 128 is raised into the position shown in dotted lines in Fig. 6. Thereby the plate 172 is retracted as described above and the screw bolt 134 brought into contact with the contact piece 142 thus establishing an electrical connection between the current lead 170 and the end 148 of the heating winding as more fully described hereabove. The pressure on the press button 128 is then relieved and the parts are in the position shown in Figs. 6 and 7.

The heating of the part 122 now begins and the bimetallic strip 136 bends downward displacing the leaf spring 140, the contact piece 142, the screw bolt 134, and the snapping spring 154. When the latter has passed its neutral position it snaps suddenly into its other end position thereby interrupting the contact between the screw bolt 134 and the contact piece 142. When this happens the plate 172 is moved forward from the position shown in Fig. 6 into the position shown in Fig. 5.

Referring now to Figs. 8-11, an embodiment of my invention is shown which on the whole is similar to that shown in Figs. 5-7 with the exceptions described hereinafter. First of all the plate 172 and the spring 178 are omitted. The bimetallic strip is a double one but its parts 190 and 192 bend under the influence of heat in op-

posite directions as clearly shown in Fig. 11. The leaf spring 140 is not provided with a contact piece but it is extended so as to abut with its end 194 on the structure 120 in the open position of the switch shown in Fig. 10. Finally the connection of the screw bolt 134 with the snapping spring 154 is modified in a manner to be more fully described presently.

The threaded bolt 136 passes with clearance through a central hole 198 of the snapping spring 154. The bolt is held by a clamping member 198 in shape of a stirrup and provided in its upper flat part 202 with a central hole 200 into which the bolt 134 is screwed. The clamping member 198 is bent into U-shaped parts 204 and 206 adjoining the flat portion 202 and clasping firmly the snapping spring 154 establishing with the latter a mechanical connection as well as an electrical contact. The ends 208 and 210 of the clamping member 198 are bent so as to clamp between them the pressing button 212 which is provided with a circumferential groove 214 for engagement by the ends 208 and 210 of the clamping member 198. The upper end of the button 212 is bevelled as at 216 so that it can be pressed into position between the ends 208 and 210. In this embodiment the bolt 134 is set for a certain temperature by adjusting its position in the clamping member 198 by turning the bolt with a screw driver (not shown) attacking at the slot 218. After the setting the press button 212 is pressed into position between the ends 208 and 210 of the clamping member 198 after which the setting of the switch can be still changed through the opening in the switch button.

The operation of this device is essentially the same as that of the device shown in Figs. 5-7. When the switch is in closing position the parts have the position shown in Figs. 8 and 9, the connection between the current lead 170 and the end 148 of the heating winding being established through the snapping spring 154, the clamping member 198, the bolt 134, and the leaf spring 140. When the bimetallic strip becomes hot it assumes the position best shown in Fig. 11, in which its parts 190 and 192 are bent with the sides having the smaller coefficient of thermal expansion facing each other. Therefore the bolt 134 is pressed downwards and in the last part of its motion, which is accelerated by the snapping of the spring 154, interrupts the current. The parts are now in the position shown in Figs. 10 and 11. In order to reset the switch the press button 212 is pressed upwards. It should be noted that in this embodiment the press button 212 is at a definite distance from the bolt 134 owing to the provision of the clamping member 198.

It will be understood that each of the elements described above, or two or more together, may also find a useful application in other types of bimetallic switches differing from the types described above.

While I have illustrated and described the invention as embodied in bimetallic switches for water boilers I do not intend to be limited to the details shown, since various modifications and structural changes may be made without departing in any way from the spirit of my invention.

Without further analysis, the foregoing will so fully reveal the gist of my invention that others can by applying current knowledge readily adapt it for various applications without omitting features that, from the standpoint of prior art, fairly

constitute essential characteristics of the generic or specific aspects of this invention and, therefore, such adaptations should and are intended to be comprehended within the meaning and range of equivalence of the following claims.

What I claim as new and desire to secure by Letters Patent is:

1. A bimetallic switch comprising in combination: a bimetallic strip; a spring arranged for snapping transition from one end position into another end position; a connection between said bimetallic strip and said snapping spring causing said spring to snap into the other end position when said bimetallic strip is hot; a contact disposed between said bimetallic and said spring; said contact having a circuit-breaking position and a circuit making position; a connection between a first portion of said snapping spring and said contact causing to move said contact into circuit-breaking position when said snapping spring has moved into the other end position under action of said bimetallic strip; and manually operated means adapted to engage said snapping spring at a second portion thereof distant from said first portion of said snapping spring for bending the same from said other into said one position, operation of said manually operated means while said snapping spring is prevented from returning into said one position resulting, however, in bending of said snapping spring without its return in said one position and without consequent closing of said contact.

2. A bimetallic switch comprising in combination: a frame; a bimetallic strip; a strip-shaped snapping spring having two ends abutting against said frame; said spring being arranged for snapping transition from one end position into another end position; a connection between said bimetallic strip and said spring causing said spring to snap into the other end position when said bimetallic strip is hot; a contact disposed between said bimetallic strip and said spring; a connection between a first portion of said spring and said contact; and manually operated means adapted to engage said snapping spring at a second portion thereof distant from said first portion of said snapping spring for bending the same from said other into said one position, operation of said manually operated means while said snapping spring is prevented from returning into said one position resulting, however, in bending of said snapping spring without its return in said one position and without consequent closing of said contact.

3. A bimetallic switch comprising in combination: a frame; a bimetallic strip having ends resting against a surface adapted to be heated; a strip shaped snapping spring having two ends abutting against said frame; said spring being arranged for snapping transition from one end position into another end position; a connection between the middle portion of said bimetallic strip and said spring causing said spring to snap into the other end position when said bimetallic strip is hot; a contact disposed between said bimetallic strip and said spring; and a connection between a first portion of said spring and said contact; and manually operated means adapted to engage said snapping spring at a second portion thereof distant from said first portion of said snapping spring for bending the same from said other into said one position, operation of said manually operated means while said snapping spring is prevented from returning into said one position resulting, however, in bending of said

snapping spring without its return in said one position and without consequent closing of said contact.

4. A bimetallic switch comprising in combination: a frame; a bimetallic strip; a strip-shaped snapping spring having two ends abutting against said frame; said spring being arranged for snapping transition from one end position into another end position; a connection between said bimetallic strip and said spring causing said spring to snap into the other end position when said bimetallic strip is hot; a contact carrier; and a member shaped as a double stirrup and connecting the middle portion of said spring with said contact-carrier; and manually operated means for closing said contact.

5. A bimetallic switch comprising in combination: a frame; a bimetallic strip; a strip-shaped snapping spring having two ends abutting against said frame; said spring being arranged for snapping transition from one end position into another end position; a connection between said bimetallic strip and said spring causing said spring to snap into the other end position when said bimetallic strip is hot; a contact carrier; and a member shaped as a double stirrup and connecting the middle portion of said spring with said contact-carrier said double stirrup engaging said contact-carrier with play; and manually operated means for closing said contact.

6. A bimetallic switch comprising in combination: a frame; a bimetallic strip having ends resting against a surface adapted to be heated; a strip-shaped snapping spring having ends abutting against said frame; said spring being arranged for snapping transition from one end position into another; a contact carrier; a member shaped as a double stirrup and connecting the middle portion of said snapping spring to said contact-carrier; said double stirrup engaging said contact-carrier with play; aligned holes in said double stirrup, said contact carrier and said snapping spring; a screw thread in said hole in the part of said double stirrup engaging said snapping spring; and a screw bolt screwed into said threaded hole and extending loosely through said other holes; said screw bolt having an end arranged near the middle portion of said bimetallic strip when the latter is cold and being engaged by the middle portion of said bimetallic strip when the latter becomes hot.

7. A bimetallic switch comprising in combination: a frame; a bimetallic strip; a strip-shaped snapping spring having two ends abutting against said frame; said spring being arranged for snapping transition from one end position into another end position; a connection between said bimetallic strip and said spring causing said spring to snap into the other end position when said bimetallic strip is hot; a U-shaped strip having a stationary end; a contact rigidly connected to the other end of said U-shaped strip; and a member shaped as a double stirrup and connecting the middle portion of said spring with the leg of said U-shaped strip carrying said contact.

8. A bimetallic switch comprising in combination: a frame; a bimetallic strip having ends resting against a surface adapted to be heated; a strip-shaped snapping spring having ends abutting against said frame; said spring being arranged for snapping transition from one end position into another; a U-shaped strip having a stationary end; a contact rigidly connected to the other end of said U-shaped strip; a member shaped as a double stirrup and connecting the

middle portion of said snapping spring to the leg of said U-shaped strip carrying said contact; said double stirrup engaging said leg of said U-shaped strip carrying said contact with play; aligned holes in said double stirrup, said U-shaped strip and said snapping spring; a screw thread in said hole in the part of said double stirrup engaging said snapping spring; and a screw bolt screwed into said threaded hole and extending loosely through said other holes; said screw bolt having an end arranged near the middle portion of said bimetallic strip when the latter is cold and being engaged by the middle portion of said bimetallic strip when the latter becomes hot.

9. A bimetallic switch comprising in combination: a bimetallic strip; a strip-shaped snapping spring having stationary ends; a bolt connected to the middle portion of said spring and having an end arranged near said bimetallic strip for axial displacement of said bolt by said bimetallic strip when said bimetallic strip becomes hot; a contact arranged for actuation by a first portion of said spring, said contact being disposed between said bimetallic strip and said spring; and manually operated means adapted to engage said snapping spring at a second portion thereof distant from said first portion of said snapping spring for bending the same, operation of said manually operated means while said snapping spring is prevented from returning into the position in which said bolt is not axially displaced by said bimetallic strip resulting, however, in bending of said snapping spring without a consequent closing of said contact.

10. A bimetallic switch comprising in combination: a bimetallic strip arranged in a bottom recess of an electrically heated vessel; a strip-shaped snapping spring having stationary ends; a bolt connected to the middle portion of said spring and having an end arranged near said bimetallic strip for axial displacement of said bolt by said bimetallic strip when said bimetallic strip becomes hot; a contact arranged for actuation by a first portion of said spring, said contact being disposed between said bimetallic strip and said spring; and manually operated means adapted to engage said snapping spring at a second portion thereof distant from said first portion of said snapping spring for bending the same, operation of said manually operated means while said snapping spring is prevented from returning into the position in which said bolt is not axially displaced by said bimetallic strip resulting, however, in bending of said snapping spring without a consequent closing of said contact.

11. A bimetallic switch comprising in combination: a bimetallic strip; a strip-shaped snapping spring having stationary ends; a bolt connected to the middle portion of said spring and having an end arranged near said bimetallic strip for axial displacement of said bolt by said bimetallic strip when said bimetallic strip becomes hot; a contact arranged for actuation by a first portion of said spring; and manually operated means adapted to engage said snapping spring at a second portion thereof distant from said first portion of said snapping spring for bending the same, operation of said manually operated means while said snapping spring is prevented from returning into the position in which said bolt is not axially displaced by said bimetallic strip resulting, however, in bending of said snapping spring without a consequent closing of said contact.

12. A bimetallic switch comprising in combination: a bimetallic strip; a strip-shaped snapping spring having stationary ends; a bolt connected to the middle portion of said spring and having an end arranged near said bimetallic strip for axial displacement of said bolt by said bimetallic strip when said bimetallic strip becomes hot; a re-setting spring arranged for bringing said snapping spring into its initial position; a member arranged for pressing said resetting spring 10 against said snapping spring; and a contact arranged for actuation by said spring.

OCTAVIO JOSE ALVAREZ.
